H.W. Loudon
 Egg Beater
 No. 74837 Patented Feb. 25, 1868

Inventor.
 Henry W. Loudon

United States Patent Office.

HENRY W. LOUDEN, OF EPHRATA, PENNSYLVANIA.

Letters Patent No. 74,837, dated February 25, 1868.

IMPROVED EGG-BEATER.

The Schedule referred to in these Letters Patent and making part of the same.

TO ALL WHOM IT MAY CONCERN:

Be it known that I, HENRY W. LOUDEN, of Ephrata, in the county of Lancaster, and State of Pennsylvania, have invented a new and useful Improvement for Beating Eggs or the like, for culinary purposes; and I do hereby declare that the following is a full, clear, and exact description of the construction and operation of the same, reference being had to the accompanying drawings, making a part of this specification, in which—

Figure 1 is a perspective view of the box and top, with its gearing in place.

Figure 2, a vertical section of the entire combination.

Figure 3, a perspective view of the combined beater and gearing annexed.

Figure 4, a plan view of the gearing.

The nature of my invention consists in providing a box, of any suitable material, combined with a cover, readily put on and taken off, so geared as to revolve two or more beaters in opposite directions, by means of a crank-handle, for beating eggs, mixing cake-batter, or like culinary purposes.

To enable others skilled in the art to make and use my invention, I will proceed to describe its construction and operation.

The box K is made with a flange or rim, k, in which there are oblong slots for the reception of hooks on the lower side of the top rim t, overlapping the flange k. There is a socket or step, in the centre of the bottom of the box, to receive the central shaft A, of the beater, fig. 3. The top or cover T has a central opening and a bracket I, with a bearing for the upper end of the shaft A. There is also a sliding door, J, on a pivot, and secured in a catch on said top or cover T, besides a small pinion, G, and a pair of cogged wheels, E F, with a crank-handle, H, with their several bearings on the same. The beater consists of a shaft or spindle, A, having a cogged pinion, a, near the upper end, and an affixed beater, D D, with recurved ends, d d, near the bottom. Around this spindle A there is a pipe or sleeve, B, provided with a cogged pinion, b, coming directly under the pinion a, on the spindle A. This pipe B is provided with cross-beaters C C', so placed that the one passes through or between the beater D and its recurved ends d, and the other over the same, in their revolutions.

The operation is such that when the cover and beaters are in place, as shown by figs. 1 and 2, the upper of the larger cogged wheels E meshes into the pinion a on the spindle A. The under one, F, meshes into the independent side pinion G, which latter meshes into the pinion b, on the sleeve B. The wider or double-cogged wheel or wheels E F, being connected with the crank-handle H, impart a twofold or reverse motion, by means of the pinion G, to the respective pinions a and b, and cause the beaters D d and C C' to revolve rapidly in contrary directions, so as to produce a thorough beating and mixing of the material within the box, as can readily be understood by their action.

The compound movement may have been used for other purposes, so that I do not broadly claim the gearing, separately considered. I am not aware that any machine for beating eggs or mixing batter, for culinary purposes, has ever been used substantially in the manner specified, and knowing its utility, I believe it to be both novel and useful.

What I claim as my invention, and desire to secure by Letters Patent, is—

The arrangement of the double beaters D d C C', pipe or sleeve B, and spindle A, with the pinions a b, in combination with the box or cover K T, cogged gear and handle, substantially in the manner and for the purpose specified.

HENRY W. LOUDEN.
